Joseph N. Gaston

United States Patent Office.

JOSEPH N. GASTON, OF LYONS CITY, IOWA.

Letters Patent No. 69,793, dated October 15, 1867.

IMPROVED BUCKLE.

The Schedule referred to in these Letters Patent and making part of the same.

TO ALL WHOM IT MAY CONCERN:

Be it known that I JOSEPH N. GASTON, of Lyons City, county of Clinton, and State of Iowa, have invented a new and useful improvement in Buckle.

The object gained by my invention is less material and greater strength, there being no tongue to punch a hole for, thereby weakening the trace or belt; also greater ease of regulating the length; and I do hereby declare that the following is a full, clear, and exact description of the construction and operation of the same, reference being had to the annexed drawings, and letters of reference marked thereon, all making a part of this specification, in which—

Figure 1 is a side view of the device.

Figure 2 is a perspective view.

Figure 3 a trace or belt with the stops D D.

Figure 4 a section on line S, fig. 1.

A and B represent part of hames, showing how the device may be attached; C represents the trace-tug or strap; D D represent the stops; E represents the buckle-frame; F represents the hame draught-strap; H, J, K, and O represent the cross-bars to buckle.

Now to enable others to make and use my invention, I will proceed to describe its construction and operation. I construct the buckle E and the stops D D of any suitable material. The stops D D I fasten to the trace or strap by punching holes in the same for rivets. These holes I punch with a three-cornered awl, or any awl or punch that will not cut away the leather and thereby weaken it. These stops have a shoulder, as shown in the drawing, and are firmly fastened to the strap or trace with rivets, at proper distances for lengthening and shortening the strap or trace. The buckle is made with five cross-bars, and may be with or without the ears to attach it to straps A B. This buckle is crooked or curved in form, so that a straight line will pass over and under the bars O, J, and K. I attach the stationary strap or draught-piece firmly to the cross-bar O by sewing or riveting the same, also the straps A and B, attached in same way to the ears.

The operation of my device is as follows: After the buckle is attached to the permanent parts, take the piece that has the stops D D fastened to it and pass the end through under H, over J, under K, over O, and under P, in fig. 2. The stops D D are so constructed that they will pass through the buckle as indicated. Now draw the stop D back past the bar K, then draw the stop D against the bars K, and it will be found that the shoulder in stop will fit on said bar, and the strap or trace will be in a straight line, or nearly so, as indicated in fig. 4.

It will be seen that this arrangement has great advantage over the ordinary buckle, for there is no tongue to crimp the leather or hole to start a fracture from, thereby weakening the material.

What I claim as my invention, and desire to secure by Letters Patent, is—

The buckle-frame E and stops D D, when constructed, arranged, and operating substantially as and for the purposes set forth.
